UNITED STATES PATENT OFFICE

101,266

DESIGN FOR A LADY'S SHOE RECEPACLE

Thomas A. Batté and Walter W. Carpenter,
Los Angeles, Calif.

Application February 17, 1936, Serial No. 61,214

Term of patent 14 years

To all whom it may concern:

Be it known that we, Thomas A. Batté and Walter W. Carpenter, citizens of the United States of America, residing at Los Angeles, in the county of Los Angeles and State of California, have invented a new, original, and ornamental Design for a Lady's Shoe Receptacle of which the following is a specification, reference being had to the accompanying drawing, forming a part thereof.

Figure 1 is a perspective view of the article, showing our new design, with the cover thereof

in open position and with certain of the shoe receiving pockets hidden from view, as they extend circumferentially about the entire inner surface of the body.

Figure 2 is a perspective view thereof, on a reduced scale, with the cover in closed position.

We claim:—

The ornamental design for a lady's shoe receptacle substantially as shown and described.

THOS. A. BATTE.
WALTER W. CARPENTER.
